UNITED STATES PATENT OFFICE.

AUGUSTE HYGONNET, OF PARIS, FRANCE, ASSIGNOR TO SOCIETE GENERALE DE COUTELLERIE ET ORFEVRERIE, OF PARIS, FRANCE.

DESIGN FOR AN ASH-STAND.

56,724.

Specification for Design.

Patented Dec. 7, 1920.

Application filed June 18, 1919. Serial No. 305,188. Term of patent 14 years.

To all whom it may concern:

Be it known that I, AUGUSTE HYGONNET, a citizen of the Republic of France, residing at 31 Rue Pastourelle, Paris, in the Republic of France, have invented a new, original, and ornamental Design for an Ash-Stand, of which the following is a specification, reference being had to the accompanying drawing, forming part thereof.

The figure is a plan view of an ash stand showing my new design.

I claim:

The ornamental design for an ash stand, as shown.

AUGUSTE HYGONNET.
